UNITED STATES PATENT OFFICE.

WILLET H. MOSHER, OF BUFFALO, NEW YORK.

FURNACE.

Application filed December 13, 1926. Serial No. 154,365.

This invention relates to improvements in heating apparatus and more particularly to a gas-burning furnace for domestic purposes.

5 Its chief object is the provision of an efficient furnace of this character which is so designed and constructed that the resistance or friction to the flow of hot gas in the radiator flues practically equalizes or balances the chimney draft.

Another object of the invention is to provide a furnace which has a comparatively long flue travel for the hot gases, and which is of a minimum height to enable the use 15 of steep and direct warm air pipes to the rooms to be heated.

Other objects are to provide a furnace of this type which is simple, compact and inexpensive in construction, which can be readily 20 adjusted to produce the best results, and which can be readily assembled and dismembered.

In the accompanying drawings:—Figure 1 is a front elevation of a furnace embodying 25 my invention. Figure 2 is a side elevation thereof. Figures 3 and 4 are horizontal sections on the correspondingly numbered lines in Fig. 1. Figure 5 is a transverse vertical section on line 5—5, Fig. 1.

30 Similar characters of reference indicate corresponding parts throughout the several views.

The outside casing or shell of the furnace, which is preferably constructed of sheet 35 metal and rectangular in shape, consists of front and rear walls 10 and 11, side walls 12 and a top wall 13. In its front wall 10 the casing has an opening 14 normally closed by a door 15 and below the same is an air 40 inlet or opening 16.

Contained within the front part of the casing and spaced from the rear, top and side walls thereof is a fire box 17, which may likewise be constructed of sheet metal, and 45 is secured at its front end to the front wall 10 of said casing by suitable attaching flanges 18, as shown in Figs. 3 and 4. This fire box has openings 19 and 20 which register with the corresponding openings 14 and 50 16 in the casing, and mounted within the box are gas burners 21 or equivalent heating elements. The upper end of the fire box terminates in a dome 22 from which leads an outlet pipe 23 for the products of combustion.

Surrounding the side walls and rear wall of the fire box 17 and contained within the chamber 24 of the casing is a system of radiator flues which are so constructed and arranged that the chimney draft is practically equalized by the resistance offered to the flow of hot gases passing through such flues. To this end, a lower U-shaped flue 25 is provided which is disposed horizontally about the fire box and is supported in such 60 position on suitable legs 26. Surmounting this flue is an upper flue consisting of two connected inner and outer sections 27 and 28 the outer section 27 being of the same shape in plan as the lower flue 25 and the 65 inner section 28 being more or less square-shaped in top plan and circumscribing the outlet pipe 23 of the fire box, as shown by dotted lines in Fig. 1. Both upper and lower flues are made from sheet metal pipe 70 sections joined at the corners by suitable elbows 29 having radial fins 30 thereon, which not only increase the radiating area of the flues but also prevent the formation of eddy currents of air about the elbows. These flues 75 communicate with each other so that the hot gases pass through the upper flue in one direction and through the lower flue in a counter direction. For this purpose, the fire 80 box outlet pipe is connected with the innermost pipe-leg 31 of the upper flue-section 28 and the pipe-leg 32 of the latter is joined to the opposing pipe-leg 33 of the companion outer flue section 27. The outermost pipe-leg 34 of the latter is joined by a conduit 85 35 with the adjoining pipe-leg 36 of the lower flue 25, while the opposite parallel pipe-leg 37 thereof is connected by a conduit 38 with the chimney 39. The front ends of the pipe-legs 31, 33 and 34 of the upper flue and the 90 pipe-legs 36 and 37 of the lower flue are closed by suitable covers 40. By this arrangement, a circuitous course for the products of combustion is provided, the hot 95 gases eliminated from the fire box passing in a counter-clockwise direction through the inner section 28 of the upper flue, then through the outer section 27 thereof and thence downwardly through the conduit 35 into the lower flue 25, through which it 100 flows in a counter or clockwise direction to the chimney 39.

The radiator flues are preferably of the elongated cross-section shown, with rounded top and bottom portions, which produce 110

a large radiating surface for this cross-sectional area and afford a greater compactness of construction.

Leading from the top of the furnace-casing are warm air pipes 41 for conducting the heat to the different rooms. As the overall height of the furnace is only about four feet, these warm air pipes can be quite steep and thereby reduce the heat losses to a minimum.

The upper flue is also connected with the chimney 39 by a conduit 42, which, as shown in Fig. 1, is joined to the pipe-leg 33 of the outer section 27 of said flue. Arranged within this conduit is a normally closed damper 43 which is only opened when starting the furnace for the purpose of heating the chimney. The opening of the damper enables the hot gases to flow through the upper flue and thence directly out through the chimney. As soon as the chimney is warmed sufficiently to create a draft, the damper is closed, thereby causing the gases to flow from the upper flue into the lower one and thence out through the chimney.

By arranging the radiator flues in the manner heretofore described, the resistance to the flow of hot gases passing through them is such as to nearly equal or balance the draft of the chimney with the result that the high friction caused by the rubbing effect of the hot gases in the flues produces a maximum transfer of heat to the flue-walls and thence to the surrounding air in the furnace casing. Every furnace is most efficient at some particular rate of heat flow, and the present design may be easily and readily adapted to any rate of heat flow by adjusting the length of the radiator flues and thus give the proper resistance for that particular rate of heat production at the burner. The flues are made longer for a greater gas consumption and shorter for a smaller consumption.

Furthermore, the construction of this improved furnace is such that it can be assembled in the field by one man, and the entire fire box and radiator flue assembly may be repaired or removed without disturbing the warm air piping.

It will also be noted that the top and sides of the fire box 17 are exposed to the casing chamber 24 and the heat radiated therefrom is likewise utilized and conducted through the warm air pipes 41 to the rooms.

I claim as my invention:—

1. A heating apparatus, comprising a cas-

ing, a fire box arranged in said casing and spaced from the walls thereof to form a flue-chamber, said fire-box having an outlet in its top for the products of combustion, a chimney, a flue disposed in the upper portion of said chamber above the fire box and including interconnected inner and outer concentrically-arranged sections shaped to form a circuitous spiral like path for the products of combustion, the inner section communicating with the outlet of the fire box, and a second flue disposed in the lower portion of said chamber and connected at its inlet end to the outlet end of said first-named flue and at its outlet end to the chimney.

2. A heating apparatus, comprising a casing, a fire box arranged in said casing and spaced from the walls thereof to form a flue-chamber, said fire-box having an outlet in its top for the products of combustion, a chimney, a flue disposed in the upper portion of said chamber over the fire box and including interconnected inner and outer sections shaped to form a circuitous spiral like path for the products of combustion in one direction, the inner section encircling the outlet end of the fire box and connected at its inlet end thereto and the outer section being U-shaped and having one leg thereof connected with the adjoining end of said inner section, and a second flue of U-shape disposed in the lower portion of said chamber and partially surrounding said fire box for conducting the products of combustion in a direction counter to that of said first-named flue, one leg of said second flue being connected with the adjoining superposed leg of the outer section of said first-named flue and the other leg thereof communicating with the chimney.

3. A heating apparatus comprising a casing, a fire box arranged in said casing and having an outlet, a chimney, upper and lower flues of U-shape arranged in said casing and connected with each other at one end, conduits connecting the other ends of said flues with the chimney, and a third flue arranged within and concentric with the upper flue and connected at one end with the fire box outlet and at its other end with said upper flue, the combined lengths of the several flues being such as to resist the flow of hot gases therethru at a rate substantially equal to that of the chimney draft.
